(57) **CLAIM**

I claim the ornamental design for a food pan rack, as shown and described.

DESCRIPTION

FIG. 1 shows a right hand perspective view of the food pan rack.

FIG. 2 shows a front elevation view thereof.

FIG. 3 shows a right hand side elevation view thereof.

FIG. 4 shows a left hand side elevation view thereof.

FIG. 5 shows a top plan view thereof.

FIG. 6 shows a bottom plan view thereof; and,

FIG. 7 shows a rear elevation view thereof.

The broken lines in FIG. 6 show portions of the food pan rack which form no part of the claimed design.
